(57) **CLAIM**

The ornamental design for a vehicle light assembly, as shown and described.

DESCRIPTION

FIG. 1 is a perspective view of a lighting assembly showing my new design.

FIG. 2 is a rear elevational view thereof, the opposite side having a flat backing; and,

FIG. 3 is a rear elevational view of another embodiment thereof, the opposite side having a flat backing.

The broken line showing of a vehicle is for illustrative purposes only and forms no part of the claimed design.
